CLAIM

The ornamental design for a combined book holder and light assembly, as shown and described.

DESCRIPTION

FIG. 1 is a perspective view of a combined book holder and light assembly showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof; and
FIG. 7 is a left side elevational view thereof.
An intermediate portion of the conventional power cord has been broken away and omitted for convenience of illustration.
